ROTARY PUMP.

1,180,613.

Specification of Letters Patent. Patented Apr. 25, 1916.

Application filed March 19, 1913. Serial No. 755,439.

To all whom it may concern:

Be it known that I, OTTO SIEMEN, a citizen of the German Empire, and residing at Nonnendamm, near Berlin, Germany, have 5 invented certain new and useful Improvements in Rotary Pumps, of which the following is a specification.

My invention relates to rotary pumps of the known type in which the blade-wheel 10 is journaled eccentrically in the pump-casing, the various spaces or cells formed by each two blades being packed at the side nearest the casing by a ring of liquid formed in the casing by centrifugal action due to 15 the rapid rotation of the blade-wheel. These pumps are particularly suitable for conveying gases, such as air or for taking in steam to deliver the same in condensed condition, and enable a high vacuum to be produced. 20 At a given speed of rotation they are suitable, however, only for one predetermined ratio of suction and delivery pressures.

The pump according to my present invention is suitable for exhausting and conveying 25 gases and vapors and especially for the exhaustion of water vapor, that is to say, a mixture of steam and air, and is actually employed in practice for condensing plants 30 for the purpose of drawing off the condensing steam of reciprocating steam engines and steam turbines. The mixture of steam and air is carried from the condenser into the pump, and immediately after entering 35 the pump the steam of said mixture will be condensed by action of the liquid ring and in this manner only air be carried by the pump. Pumps with liquid ring as compared with dry plunger pumps have the advantage 40 of being of smaller size for the same quantity of the condensed water. The reason for this is found therein that in pumps with liquid ring the steam is immediately condensed so that only air will be carried 45 in the pump, while a dry pump will not cause the condensing of the steam after its entrance and consequently a mixture of steam and air will be carried through the pump.

50 By the term ratio of suction and delivery pressures there will be understood the ratio between the pressure existing at the suction side and the pressure existing at the pressure side. In case the pumps have normal inlet 55 and exhaust openings this pressure ratio

of the pump is constant, assuming a constant peripheral velocity of the pump wheel, while in the pump according to my present invention this pressure ratio will be variable for the same peripheral velocity. 60

A primary object of my invention is to make a pump of the described type adapt itself automatically to a variable ratio of suction and delivery pressures. To effect this, both the magnitude of the outlet opening and relative position of the outlet and inlet openings of the pump must vary automatically according to the desired ratio. 65

According to my invention I attain this end by making the outlet opening not as 70 one continuous opening, but subdivided into several separate openings or ports arranged one behind another in the direction of flow of the medium to be conveyed; these individual openings or ports are closed and 75 opened in the discharge chamber of the pump by a liquid or by solid bodies which acts or act like valves.

Several illustrative embodiments of my invention are represented by way of example 80 in the accompanying drawing, wherein:—

Figure 1 is a vertical section through the pump taken at right angles to its shaft, and Fig. 2 is a like view taken on the line A—B in Fig. 1. Fig. 3 is an elevation showing 85 the suction and discharge chambers of the pump after one of the covers has been removed; it shows the plate having the inlet and outlet openings as seen from the side opposite to that shown in Fig. 1. Figs. 4 to 10 are detail views showing modified 90 forms of the outlet openings of the pump described hereinafter.

Referring firstly to Figs. 1 to 3, *a* designates the casing of the pump in which the 95 eccentrically journaled blade-wheel *b* rotates in the direction indicated by the arrow shown in Fig. 1. The blades *h* of this wheel approach the casing nearest at the line *a*, hereinafter termed the crown. Fast 100 on the shaft *f* of the pump is the boss or hub *g* of the wheel on which are fastened the blades *h*.

c designates the inlet opening, while *d*, *d*₁ 105 designate the subdivided outlet opening of the pump also provided in the plate *p*. The medium to be propelled enters through the supply pipe *i* into the suction chamber *k*, flows thence through the inlet opening *c* into the casing *a* and is driven by the blade- 110

wheel through the subdivided outlet opening into the discharge chamber m and into the delivery pipe n connected to this chamber m at the top thereof. The suction chamber k and the discharge chamber m are separated from one another by the wall or rib o ; they are bounded on the one side by the said plate p and are closed on the other side by the cover q .

- 10 The water requisite for forming the rotating ring of liquid is constantly replenished. The excess water flows away into the discharge chamber m and completely fills this because the delivery pipe n is connected to the top thereof. The subdivided outlet opening in the plate p is consequently closed gas-tight by water in the discharge chamber.

Assuming the pump to operate as a gas or air compressing pump its action is as follows:—When the ratio of the suction and delivery pressures is great the gas or air sucked in is not discharged at those ports d_1 which are located farthest from the crown a_1 because it has not yet at this place been compressed to a pressure exceeding the high pressure existing in the discharge chamber m . On the contrary liquid will flow back out of the discharge chamber m through these lowest ports d_1 into the casing a . The quantity of such liquid which flows back is, however, relatively very small because the velocity at which water moves is materially less than that of air at the same pressure. Thus the water in the subdivided outlet opening in the plate p constitutes a closure member whose action perfectly corresponds to that of a non-return or check valve.

- 40 In case of a prescribed speed of rotation of the pump according to my invention a definite compression path for the suction opening c to the pressure opening d will be required in order to attain a definite pressure ratio. If this pressure ratio is small, the quantity of the gas drawn off is only little decreased and this gas will be carried through all discharge openings d into the exhaust space m , thus rendering the 50 path of compression small. If however a high pressure ratio between suction and pressure side shall be attained, the quantity of the gas drawn off must be considerably decreased and for the same speed of rotation 55 of the pump a longer path of compression will be necessary.

By the arrangement according to my present invention the magnitude of the discharge openings will be automatically decreased in case of a great pressure ratio and thereby the path of compression will be prolonged by keeping closed the discharge openings d which are at a greatest distance from the vertex a_1 of the pump.

- 65 In Figs. 3 to 10 various forms or arrange-

ments of the subdivided outlet opening are represented. Fig. 3 shows simple round orifices or ports d_1 located one behind another in rows in the direction of flow of the medium being conveyed. The portion d of the opening located nearest the crown a_1 need not be subdivided, but may be continuous, as shown in Figs. 1, 3, 4, 5 and 7. Instead of round orifices oval slots d_2 may be provided, as shown in Fig. 4.

70 The above described valve-like action can be increased by forming the orifices as passages, because the increased friction offers increased resistance to the water. Such an arrangement is shown in Fig. 5, in which 80 downwardly directed tubes d_3 are shown connected to the outlet orifices.

75 Instead of forming the passages as tubes they may be arranged as covered channels or passages d_4 cast in the plate p , as clearly 85 shown in Fig. 6.

In order to prevent the medium which is being propelled and issues out of the opening d located near the crown returning through the lower outlet orifices into the 90 pump, as shown in Fig. 5 the passages or tubes may extend down to various depths in the discharge chamber, the lower orifices being connected with tubes which open low down in the chamber, while the upper orifices are connected to tubes which open higher up. Also, it may be preferable to 95 separate the orifices located beside one another in a row by means of walls or partitions, as shown in Fig. 7. Such partitions 100 may also be employed between the outlets of passages arranged in the plate d itself. When tubes are employed the purpose in view is obtained when, as shown in Fig. 8, the lower ends of the downwardly directed 105 tubes are bent upward.

Instead of obtaining the valve action by means of orifices or ports closed by water in the discharge chamber, this valve action may, of course, be obtained by means of 110 mechanical valves t which, as shown in Fig. 9, are formed as ball-valves. If desired, flap valves may be employed.

In Fig. 1 the inlet opening c is shown as one connected opening. If desired, there is, 115 of course, no objection to subdividing this opening also into various smaller orifices and providing them with valves. The medium being conveyed will then be prevented from flowing back into the suction chamber when 120 it is sufficiently compressed at those parts of the suction opening which are located farthest from the crown a_1 .

In order as much as possible to diminish 125 loss of pressure when the medium being conveyed flows out of the interior of the pump without, however, facilitating the return of the liquid, the openings or ports in the plate p may be made wider at the inner side of the plate than at the side bounding the dis- 130

charge chamber; such a wide mouthed port
is represented in Fig. 10.

The rotary pump shown in Figs. 1 and 2
has the supply and delivery pipe for the me-
dium to be conveyed on only one side of the
pump. It is, of course, possible to provide
supply and delivery pipes on both sides of
the pump, or, for example, radially from
and to the interior of the blade-wheel.

10. In order to obtain a high ratio of com-
pression several pumps of the type described
may be connected in series in a common or
in separate casings.

I claim:—

15. 1. In a rotary pump of the character de-
scribed, the combination of a casing having
an inlet opening and an outlet opening, a
blade-wheel mounted eccentrically in the
casing and adapted, when rapidly rotated, to
20 cause liquid supplied into the casing to as-
sume the form of a rotating ring in the cas-
ing, and a discharge chamber having a de-
livery outlet in the upper part thereof and
being connected by way of said outlet open-
25 ing with the interior of the casing; said out-
let opening being subdivided into a plural-
ity of separate orifices located one behind
another in the direction of rotation of the
ring of liquid, and the discharge chamber
30 being normally filled with liquid for closing
and opening the said orifices in the manner
of a valve.

2. In a rotary pump of the character de-
scribed, the combination of a casing having
35 an inlet opening and an outlet opening, a
blade-wheel mounted eccentrically in the
casing and adapted, when rapidly rotated,
to cause liquid supplied into the casing to as-
sume the form of a rotating ring in the cas-
40 ing, and a discharge chamber having a de-
livery outlet in the upper part thereof and
being connected by way of said outlet open-
ing with the interior of the casing; said out-
let opening being subdivided into a plural-
45 ity of separate passages located one behind
another in the direction of rotation of the
ring of liquid, and the discharge chamber
being normally filled with liquid for closing
and opening the said passages in the manner
50 of a valve.

3. In a rotary pump of the character de-
scribed, the combination of a casing having
55 an inlet opening and an outlet opening, a
blade-wheel mounted eccentrically in the
casing and adapted, when rapidly rotated,
to cause liquid supplied into the casing to as-
sume the form of a rotating ring in the cas-
60 ing, and a discharge chamber having a de-
livery outlet in the upper part thereof and
being connected by way of said outlet open-
ing with the interior of the casing; said out-
let opening being subdivided into a plural-
65 ity of separate orifices located one behind
another in the direction of rotation of the
ring of liquid, tubes in the discharge cham-

ber each having one end connected to one of
said orifices, and the discharge chamber be-
ing normally filled with liquid for closing
and opening the other ends of said tubes in
the manner of a valve.

4. In a rotary pump of the character de-
scribed, the combination of a casing having
an inlet opening and an outlet opening, a
blade-wheel mounted eccentrically in the
casing and adapted, when rapidly rotated,
70 to cause liquid supplied into the casing to
assume the form of a rotating ring in the
casing, and a discharge chamber having a
delivery outlet in the upper part thereof
and being connected by way of said outlet
80 opening with the interior of the casing;
said outlet opening being subdivided into a
plurality of separate passages located one
behind another in the direction of rotation
of the ring of liquid, and the discharge
85 chamber being normally filled with liquid
for closing and opening the said passages
in the manner of a valve, the passages con-
nected to orifices located farther from the
crown of the casing opening into the dis-
charge chamber lower down than the pas-
sages connected to orifices located nearer the
crown.

5. In a rotary pump of the character de-
scribed, the combination of a casing, a plate
having an inlet opening and a subdivided
outlet opening dividing the casing into two
chambers, a blade-wheel mounted eccentrically
95 in one of said chambers and adapted,
when rapidly rotated, to cause liquid supplied
into the chamber to take up the form of a
rotating ring in the chamber, a wall divid-
ing the other of said chambers into a supply
100 chamber connected with said inlet opening
and into a discharge chamber connected with
said outlet opening, the supply chamber
having a supply inlet, and the discharge
chamber having a delivery outlet in the up-
105 per part thereof, the subdivisions or ports
of the outlet opening being located in one
or more rows in the direction of rotation of
the blade-wheel, and the discharge chamber
being normally filled with liquid for closing
110 and opening the subdivisions of the outlet
opening in the manner of a valve.

6. In a rotary pump of the character de-
scribed, the combination of a casing having
an inlet opening and an outlet opening, a
blade-wheel mounted eccentrically in the
casing and adapted, when rapidly rotated,
120 to cause liquid supplied into the casing to
assume the form of a rotating ring in the
casing, and a discharge chamber having a
delivery outlet in the upper part thereof
and being connected by way of said outlet
125 opening with the interior of the casing;
said outlet opening being subdivided into a
plurality of separate orifices located one
behind another in the direction of rotation
of the ring of liquid and the discharge cham-

ber being normally filled with liquid for closing and opening the said orifices in the manner of a valve; and partitions in the discharge chamber located between the orifices.

7. In a rotary pump of the character described, the combination of a casing having an inlet opening and an outlet opening, a blade-wheel mounted eccentrically in the 10 casing and adapted, when rapidly rotated, to cause liquid supplied into the casing to assume the form of a rotating ring in the casing, and a discharge chamber having a delivery outlet in the upper part thereof 15 and being connected by way of said outlet

opening with the interior of the casing; said outlet opening being subdivided into a plurality of separate orifices located one behind another in the direction of rotation of the ring of liquid, and valves opening away 20 from the blade-wheel in the orifices located farther away from the crown of the casing.

In testimony whereof I have signed my name to this specification in the presence of two witnesses.

OTTO SIEMEN.
